GAS-OPERATED SELF-LOADING FIREARM

Carl G. Swebilius, Hamden, Conn.

Application December 18, 1947, Serial No. 792,496

1 Claim. (Cl. 89—191)

1

The present invention relates in general to firearms and more especially to a self-loading firearm having improved gas-operated action-slide mechanism.

An object of the invention is to provide a superior gas-operated self-loading firearm.

A further object of the invention is to provide a self-loading firearm having superior gas-operated action-slide mechanism wherein the elements thereof are symmetrically arranged in an economy of space so as to effect maximum efficiency, minimum wear, and smooth and uniform operation of the firearm.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken side elevation partly in section on the vertical longitudinal axis of a gas-operated self-loading firearm embodying the improved gas-operated action-slide mechanism of this invention, the action being in its closed position;

Fig. 2 is a broke side elevation partly in section of the firearm shown in Fig. 1, but with the action open;

Fig. 3 is a broken bottom plan view of the firearm shown in Fig. 1, but with the fore-end removed;

Fig. 4 is a section of the barrel, action-slide, yoke and fore-end assembly on line 4—4 of Fig. 1;

Fig. 5 is a section on line 5—5 of Fig. 1 showing the tongue-portion of the fore-end nested in the flanged guard-plate on the forward end of the receiver;

Fig. 6 is an exploded fragmentary perspective view of the action-slide block and the action-slide operating-mechanism; and

Fig. 7 is a perspective view of the action-spring guide-rod and the buffer for the action-slide operating-means.

Referring to Fig. 1, the particular firearm selected for the purpose of illustrating one embodiment of the invention is a self-loading gas-operated firearm comprising, in general, a receiver 10, a barrel 11 secured to the forward end of the receiver, a buttstock 12 having a trigger-plate 13 mounted on the forward end thereof, the latter being arranged to be demountably secured on the underside of the receiver and to provide

an end-closure for the open rear end of the receiver, and gas-operated action-slide means indicated generally at 14 mounted on the underside of the barrel and adapted normally to be concealed by a wooden fore-end 15. The receiver 10 and trigger-plate 13 may be viewed together as constituting a frame for the action and fire-control mechanism of the firearm.

The action or breech-bolt 16 is mounted in the chamber 17 of the receiver for longitudinal movement to and from breech-closing position and is adapted to be automatically locked in the latter position by elevation of the upper edge of its rear end 18 into engagement with a stop-shoulder 19 on the underside of the top wall of the receiver. The forward and rearward movements of the breech-block, including locking and unlocking of the latter in the chamber of the receiver, are accomplished by the action-slide means 14 and 20 more especially by a lost-motion linkage embodying a pair of action-slides 20 supported in longitudinal guide-slots 21 in opposite sides respectively of the receiver for reciprocable movement therein, the action-slides being pivotally connected at their rear ends to the breechblock by a transverse pin 22 engaged in a rocker-shaped cam-slot 23 formed in a tongue 24 depending substantially vertically from the underside of the breechblock adjacent the rear end thereof. The action-slides 20 extend forwardly from the chamber of the receiver through suitable guide-apertures 25 in the front wall 26 of the receiver and on opposite sides respectively of the barrel, the forward ends of the action-slides 20 being fixedly secured to opposite sides respectively of an action slide block 27 hereinafter described.

Other details of the breechblock such as, for example, the spring-loaded firing-pin indicated generally at 28 and the extractor-claw 29, as well as the locking and unlocking operations of the breechblock by reciprocation of the pair of action-slides 20, are well known and characteristic features of firearms of this particular type and since they relate only generally to the invention, a more detailed description of these ancillary features is omitted. Similarly, a description of the fire-control mechanism indicated generally by the trigger 30 and hammer 31, is unnecessary to a clear and full disclosure of the present invention and, hence, has been omitted. For a complete description of the fire-control mechanism for this type of firearm, reference may be had to my co-pending application Serial No. 739,997 filed April 8, 1947.

The action-slide block 27 is a solid substan-

tially-rectangular member supported beneath the barrel by the afore-mentioned action-slides 28 for longitudinal movement relative to the barrel, the forward ends of the slides 28 being fixedly secured on opposite sides respectively of the block, as described and illustrated more fully in my co-pending application Serial No. 746,971, filed May 9, 1947. Referring particularly to Figs. 4 and 6, the top side of the action-slide block 27 is provided with a longitudinal shallow recess 32 which intersects the opposite ends respectively of the block and comprises a cylindrical surface of revolution concentric to the periphery of the barrel, the recess 32 being symmetrical with respect to the longitudinal axis of the latter and the axis of the action-slide block 27 so as to provide clearance for the barrel and yet enable the block 27 to hug the underside thereof.

The bottom of the slide-block is shown provided with a longitudinal substantially-rectangular groove 33 which is symmetrical with respect to the longitudinal axis of the block and intersects the opposite ends thereof, the width of the groove being substantially equal to the width of the yoke-portion of the action-slide operating-means hereinafter described.

The aforementioned action-slide operating-means is indicated generally at 34 and comprises an elongated hollow cylindrical connecting-rod 35 hereinafter referred to as a "tubular conrod" provided at its rear end with a yoke-portion 36 and at its forward end with a piston hereinafter described. The yoke-portion 36 is preferably formed integrally on the rear end of the tubular conrod, although it may be formed separately and secured thereto in any suitable manner, and comprises an elongated substantially-rectangular block approximately equal in length to the length of the tubular conrod 35. The bottom 37 of the yoke-portion or block 36 of the tubular conrod constitutes a cylindrical surface of revolution which is concentric with the underside of the tubular conrod and in the present embodiment is of slightly-larger radius so as to form a shoulder 38 at the intersection of the forward end of the block 36 with the rear end of the tubular conrod. The latter construction is preferred from the standpoint of good machine design and strength but it will be clear that the bottom of the yoke and the underside of the tubular conrod may constitute a smooth uninterrupted cylindrical surface of revolution.

The yoke-portion or block 36 of the tubular conrod is generally rectangular in cross section with the exception of its aforementioned curvilinear bottom 37. Formed in the lower half of the block 36 and concentric to its curvilinear bottom 37 is a longitudinal aperture 39 which intersects the rear end of the block 36 and extends forwardly therethrough to intersect the rear end of the tubular conrod 35, the diameter of the longitudinal aperture 39 being equal to the diameter of the bore 40 of the tubular conrod 35 so as to form a continuous chamber 39-40 of uniform internal diameter for accommodating the action-return spring, as hereinafter described. The opposite sides 41 of the yoke-portion or block 36 extend upwardly substantially vertically from the curvilinear bottom 37 of the block to its substantially-flat top 42 which is at right angles to its vertical sides 41, the height of the sides 41 being substantially twice the diameter of the tubular conrod 35 whereby the top 42 of the yoke-portion is elevated above the upper surface thereof. The forward end of the yoke-portion 36 thus

forms a substantially-square shoulder 43 with the rear end of the tubular conrod 35.

Milled or otherwise formed in the flat top 42 of the yoke-portion 36 is a substantially-rectangular recess 44 which extends laterally across the width of the top 42 and longitudinally thereof from a point adjacent the shoulder 43 rearwardly a distance equal to the length of the action-slide block 27. Further, the width of the yoke-portion 36 of the tubular conrod 35 is substantially equal to the width of the longitudinal groove 33 in the underside of the action-slide block 27 (see Fig. 4), as a consequence of which the recessed portion 44 of the yoke 36 is adapted to fit nicely into the groove 33 of the action-slide block 27 with the bottom of the recess 44 in engagement with the top wall of its groove 33 and the front and rear shoulders 45 and 46 respectively of the recess 44 fitting snugly against the front and rear faces respectively of the action-slide block 27, as shown especially well in Fig. 1. When assembled thusly, the yoke 36 and action-slide block 27 are adapted to be fastened together by a transverse pin 47 which is driven through transverse axially-aligned apertures 48 and 49 respectively of the action-slide block and yoke.

The forward end of the tubular conrod 35 is closed by the rear wall 50 of a solid piston 51 which is of slightly-reduced diameter and is terminated at its forward extremity by a relatively-narrow annular flange or piston-head 52 arranged to make a smooth gas-tight sliding fit in the piston-chamber of the gas-cylinder.

The gas-cylinder is indicated generally at 53 (see Figs. 1 and 2) and comprises a rearwardly-opening piston-chamber 54 which communicates with the bore of the barrel by a gas-passage 55. The latter is substantially perpendicular to the longitudinal axis of the piston-chamber 54 and is formed in a web 56 which joins the gas-cylinder 53 integrally to a sleeve 57 fixedly secured to the barrel substantially intermediate the opposite ends thereof, the sleeve 57 and web 56 constituting means for supporting the gas-cylinder 53 and its piston-chamber 54 on the underside of the barrel substantially parallel to its longitudinal axis and in the vertical plane thereof, as shown to advantage in Fig. 3. The upper end of the gas-passage 55 intersects the bore of the barrel substantially intermediate the opposite ends of the barrel-sleeve while the lower end of the gas-passage 55 intersects the piston-chamber adjacent the forward blind end 58 thereof.

In the present embodiment, the gas-cylinder 53 embodies a rearwardly-extending axially-aligned cylindrical sleeve 59 which is substantially one and one-half times as long as the gas-cylinder and is formed separately thereof, being joined thereto at its forward end by a soldered or welded joint. The bore of the sleeve 59 is equal in diameter to the bore of the piston-chamber 54 and hence forms a rear extension thereof, the over-all length of the resultant piston-chamber corresponding substantially to the travel of the breechblock in moving from breech-closing to breech-open position and vice versa.

The action-slide operating-means 34 embodies resilient-means for resisting rearward displacement thereof on discharge of the firearm and for thereafter returning the action-slide operating-means and breechblock to their normal forward positions, as shown in Fig. 2. In the present embodiment, the aforesaid resilient-means comprises a coil-spring 60 adapted to be sup-

ported throughout a major portion of its length in the longitudinal chamber 39—40 of the action-slide operating-means 34, the forward end of the coil-spring 60, hereinafter referred to as an "action-spring," being in engagement with an abutment which, in the present embodiment, constitutes the rear wall 50 of the solid piston 51. In the normal position of the action-slide operating-means 34, a portion of the action-spring extends rearwardly beyond the rear end of the chamber 39—40 and is adapted to be supported by guide-means comprising a solid rod 61 which is supported, in turn, within the convolutions of the action-spring, the forward end of the rod 61 extending into the rear end of the action-spring chamber 39—40. The rear end of the guide-rod is adapted to seat in an aperture or socket 62 formed in the front wall 26 of the receiver immediately beneath the barrel. Secured on the guide-rod adjacent its rear end and concentric thereto, is a buffer-means 63 comprising a substantially-solid cylindrical-member of hard fiber or equivalent material (see Fig. 7), the forward face of which provides both a stop for the rearwardly-moving action-slide operating-means 34 and a seat for the rear extremity of the action-spring 60.

The fore-end 15 of the firearm is adapted to be supported on the underside of the barrel, forwardly of the front wall 26 of the receiver, so as to completely enclose the above-described action-slide mechanism and the gas-operated means thereof. To this end, a guard-member 64 is provided (see Figs. 3 and 5) comprising a substantially-rectangular plate having a pair of laterally-spaced apertures 65 adjacent its upper end to accommodate the respective action-slides 20 and an aperture 66 adjacent its lower edge and in axial alignment with the socket 62 in the front wall of the receiver, to receive the spring-guide rod 61. The guard-plate 64 is adapted thus to be mounted against the front wall of the receiver, with the front face of the guard-plate constituting a seat for the rear face of the cylindrical buffer 63. The force of the action-spring thrusting against the buffer, thus serves to hold the guard-plate in its assembled position on the firearm. The guard-plate is provided, moreover, with a peripheral flange 67 bent forwardly substantially perpendicular thereto.

Referring to Fig. 4, the fore-end 15 is provided with a longitudinal axial groove in its top side to accommodate the action-slide mechanism and its operating-means 34, the upper edges of the groove having longitudinal inwardly-projecting lips adapted to extend over the corresponding upper edges of the action-slide block and action-slides to fully enclose the latter. The rear end of the fore-end is provided with a peripheral tongue-portion 68 (see Figs. 1 and 2) adapted to engage tightly with the inner walls of the peripheral flange 67 of the guard-plate, as indicated in Fig. 5, so as to firmly support the rear end of the fore-end. The forward end of the latter is secured to the barrel by a transverse screw 69 extending through apertures in opposite sides of the fore-end and an axially-aligned aperture 70 in the web of the barrel-sleeve.

The operation of the firearm is like that of similar gas-operated self-loading firearms and it will suffice to state that when the firearm is discharged, the high-pressure gas which is developed in the chamber of the barrel and drives the projectile forwardly out of the forward end

thereof, escapes in part through the gas-passage 55 into the forward end of the piston-chamber 54 and acts against the piston-head 52 to drive the latter rearwardly in the piston-chamber 54 and its cylindrical extension 59. As the piston moves rearwardly, its tubular conrod 35, including its yoke-portion 36 which connects the piston to the action-slide block 27, forces the latter and its pair of action-slides 20 rearwardly, thereby unlocking the breechblock from the stop-shoulder 19 of the receiver and moving the breechblock rearwardly to extract and eject the fired cartridge. During the rearward movement of the piston and action-slide assembly, the action-spring 60 is compressed. It will be appreciated, of course, that the strength of the action-spring is nicely balanced with the gas pressures developed within the piston-chamber so that the breechblock may complete its rearward excursion in the receiver. In this connection, it will be noted that the distance between the front face of the buffer 63 and the rear end of the yoke-portion 37 of the action-slide operating-means (when the latter is in its normal forward position) is substantially equal to the distance traveled by the breechblock in moving rearwardly from its closed position to breech-open position. The breechblock is adapted thus to be positively stopped at the end of its rearward excursion by engagement of the rear end of the yoke with the front face of the buffer, so as to prevent the rear end of the breechblock from striking the end-closure of the receiver.

As soon as the gas pressures diminish in the piston-chamber below the force of the compressed action-spring 60, the latter thereupon moves the piston action-slide assembly and breechblock forwardly into their respective normal positions, the forward movement of the breechblock being accompanied by the feeding of a fresh cartridge from the box-magazine of the firearm into the chamber of the barrel. At the end of its forward movement, the rear end of the breechblock is elevated into locking engagement with the stop-shoulder 19 of the receiver, and the firearm is ready to discharge the next cartridge.

From the foregoing description it will be clear that the action-slide operating-means 34 and gas-cylinder 53 are mounted on the underside of the barrel parallel to the longitudinal axis thereof and that by providing the piston of the piston-chamber 54 with a tubular conrod 35 having a yoke-portion at its rear end adapted to connect the piston to the action-slide block 27, the action-spring of the firearm is adapted to be supported within the tubular conrod in axial alignment with the piston and substantially parallel to the longitudinal axis of the barrel. In accordance with this construction, the force of the spring 60 acting to resist the rearward movement of the piston and action-slide assembly, acts in axial alignment with the pressure exerted on the piston-head by the gases of explosion, whereby the maximum strength of the action-spring is utilized, as a consequence of which a relatively-small spring may be used, resulting in a more compact and neater design. Moreover, by reason of the symmetrical arrangement of the action-slide operating-means 34 (including its action-spring 60) and the action-slide block 27 and its pair of action-slides 20, the forces which drive the breechblock rearwardly in the receiver and return the breechblock to breech-closing position, are evenly divided on opposite sides respectively of the breech-block and act in the longitudinal direction of its

movement, thus eliminating any unbalanced force moments which heretofore have been the source of lateral thrusts and hence excessive friction and wear on these sliding elements of the firearm.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

A gas-operated self-loading firearm, including in combination: a receiver; a breechblock movably mounted in said receiver; a barrel projecting forwardly from said receiver; a gas-cylinder on the underside of said barrel having a rearwardly-opening piston-chamber communicating with the bore of said barrel; action-slide means comprising a slide-block reciprocably mounted on the underside of said barrel, said slide-block having a groove in the underside thereof and a pair of spaced parallel action-bars extending rearwardly from said slide-block on opposite sides respectively of said barrel; said action-bars being connected at their rear ends to said breechblock; and operating-means for said action-slide means comprising a rearwardly-opening tubular-conrod mounted on the underside of said barrel substantially parallel thereto and in the vertical plane of said slide-block, said conrod having a solid piston at its forward end reciprocably engaged in the said rearwardly-opening piston-chamber, a yoke at the rear end of said tubular conrod, said yoke

being arranged to fit snugly in the groove of said slide-block to couple said conrod thereto for movement in a plane substantially parallel to the longitudinal axis of said barrel and coincident with the vertical plane of said slide-block but below its longitudinal axis, fastening means arranged to secure said slide-block and yoke together in coupled relationship, a coil-spring housed throughout a major portion of its length in the rearwardly-opening tubular-conrod, the forward end of said spring being arranged to abut the rear wall of said solid piston, a spring-guide comprising a rod supported axially within said coil-spring and arranged to engage at its forward end in the open rear end of said tubular-conrod and to seat at its rear end in a socket in the front wall of said receiver; and a buffer-member comprising a substantially-solid hard-fiber cylinder mounted on said guide-rod, the rear end of said buffer-member being arranged to engage against the front wall of said receiver and the forward end of said buffer-member constituting a fixed abutment both for the rear end of said coil-spring and said yoke.
